RECUPERATOR TILE STRUCTURE

William A. Morton, Mount Lebanon, and Howard F. Spencer, Pittsburgh, Pa., assignors to Amco, Incorporated, Pittsburgh, Pa., a corporation of Pennsylvania

Application August 7, 1934, Serial No. 738,868

2 Claims. (CL 263—20)

This invention relates to new and useful improvements in recuperator structures more particularly recuperator tile structures which constitute the preheated air and waste gas passage, 5 and it is among the objects thereof to provide a recuperator tile of a shape to produce a maximum exchange of heat between the waste gases passing on one side of the tile wall and the air passing on the opposite side of the tile wall.

10 It is a further object of the invention to provide recuperator tile which shall, because of its shape, produce stream-line effect to air flow, whereby turbulence on the tile faces is substantially eliminated, and which shall further be adapted to the use of tile of smaller cross-sectional area permitting lighter wall construction to reduce the temperature differential on the inner and outer walls of the tile thereby reducing stress that causes breakage.

15 Still a further object of the invention is the provision of a tile form which may be arranged within different shaped recuperator walls of equal areas so that the same number of tile may be employed.

20 These and other objects of the invention will become more apparent from a consideration of the accompanying drawings constituting a part hereof in which like reference characters designate like parts and in which:

25 Fig. 1 is a vertical cross-sectional view of a recuperator structure embodying the principles of this invention;

30 Figs. 2, 3 and 4 horizontal cross-sectional views of the tile structure showing different arrangements of the flue tile;

35 Fig. 5 a diagrammatic view illustrating the flow of air around and between the tile;

Fig. 6 a view in perspective of a flange or spacer tile;

40 Fig. 7 a view in perspective of a closure tile;

Fig. 8 a cross-sectional view partially in elevation of a detailed portion of the flue tile assembly;

Fig. 9 a view in perspective of a flue tile;

45 Fig. 10 a view in perspective of an end tile; and

Fig. 11 a view in perspective of a corner tile.

With reference to Fig. 1 of the drawings, the structure therein illustrated comprises a closure which is generally of a rectangular shape and 50 constructed of refractory heat insulating walls 1 in which are mounted the recuperator tile generally designated by the reference numeral 2, the tile forming vertical waste gas passages 3 and horizontal air passages 4, the air traversing the 55 horizontal passages in the manner indicated by

single arrows to the preheat air outlets 5 and 6 at the top of the tile structure. Outlets 5 and 6 communicate with preheat air passage 7 leading to the combustion chamber of a furnace. The numeral 8 designates a waste gas inlet passage to the recuperator structure, the numeral 9 a collecting chamber at the bottom of the recuperator tile structure which is in communication through passage 10 with a passage 11 leading to a stack, the waste gas flow being designated by double arrows.

An air inlet passage 12 is provided adjacent the bottom row of tile and a blower 13 may be employed to supply a regulated volume of air to be preheated.

15 While the construction shown in Fig. 1 may be illustrative of a recuperator employing either square, round or other shaped tiles as is disclosed in my Patent #1,587,171, I have discovered that a polygonal shaped tile as shown in Fig. 9 of the drawings possesses greater advantages and is adapted for arrangement in the manner shown in Figs. 2 to 4 inclusive of the drawings. In Fig. 9 an octagonal shape flue tile is designated by the reference numeral 14 and is necked at 15 at 20 one end to cooperate with a recess 16 of a flange or spacer tile 17, the latter being provided with shoulders 18 to seat the flanges 19 of a closure or baffle tile 20.

The manner of assembling the flue tile is illustrated in Fig. 8 in which the spacer tile 17 is shown at the respective ends of the flue tile 14 with the closure and baffle tile 20 inserted at the point of juncture of the spacer tile. The ends of the flue tile 14 are sealed off with cement designated by the numeral 21.

30 With reference to Fig. 2 of the drawings, it will be apparent that the flue and the flange tile 14 and 17 respectively are symmetrical, arranged with the closure tile 20, sealing off the openings 40 between the flange tile. The edge tile 22, Fig. 9, is placed between adjacent flanges 17 as shown in Fig. 2, and corner tile 23 is placed in the corners as shown in Fig. 2, the edge and corner tile being provided with shoulders 24 for seating on the flange tile 17 as shown in the upper right hand corner of Fig. 2. It is to be noted that the polygonal shaped flue tile is arranged with their juxtaposed surfaces in parallelism.

45 Fig. 3 illustrates another arrangement of the flue tile, and Fig. 4 still another arrangement, the arrangement of Fig. 3 being for a rectangular recuperator housing and that of Fig. 4 for a square housing, Fig. 3 differing from Fig. 2 in 50 55

that the recuperator housing is more narrow than that of Fig. 2.

By crowding the flange tile 17 into the narrower space in the manner shown in Fig. 3, the horizontal centers are shorter than in either construction shown in Figs. 2 or 4, and in Fig. 4 the vertical centers are shortened and the horizontal centers widened. In either case, the closure, edge and corner tile will have to be correspondingly changed to close the different shaped openings, this being commercially feasible by maintaining stock of such different types.

The merit of an octagonal form of tile as herein disclosed is that the air flowing past the outer faces of the tile flows in a stream-line to provide maximum contact or heat exchange between the waste gases passing through the flue tile and the air passing through the space between the outer walls of the tile. This is best illustrated by the diagrammatic showing in Fig. 5 wherein the arrows designate the air flow which divides to flow around the tile, then reunites between adjacent tile and is again divided, etc.

Where square tile is employed, the air flowing between adjacent tile contacts the sides of the tile only and not the transverse faces whereby a turbulence is created that lowers the heat exchange efficiency of the tile.

If round tile is employed, the same heat exchange capacity or wall area would bring the tile too close together thereby setting up resistance to the flow of air between adjacent tile so that the hexagonal form obviously is the most efficient to produce maximum surface contact of the air with the tile with a minimum of resistance of flow.

Because of the greater efficiency of the octagonal form of tile, smaller area tile may be employed which permits of thinner wall construction of the flue tile which in turn increases the conductivity of the wall and lowers the temperature differential between the inner and outer tile wall surfaces. Consequently, less breakage will occur due to this temperature differential as the thinner wall tile will be subjected to less stress than a square tile of a heavier wall section.

Another advantage of the use of octagonal tile shape is that more space is provided exteriorly of the tile structure between adjacent flue tile, thus facilitating the turning of the air flow from the bottom passages upwardly through adjacent horizontal passages so that the communicating passages between adjacent vertically disposed horizontal air flow passages can be provided

nearer the ends of the air flow passages to produce a longer path for air flow.

In its operation, a recuperator tile structure as shown in Fig. 1 functions to effect an exchange of heat between waste gases passing from the inlet 8 downwardly to the vertical passages 3 of the flue tile 14 to the collector chamber 9 at the bottom, thence through the passage 10 to the stack 11 as shown by double arrows, and air is drawn in or forced in through passage 12 following the horizontal and vertical paths as indicated by the single arrows, becoming heated by the hot waste flue tile 14, and passing into the preheated air passage 1 leading to a combustion chamber.

From the foregoing it is evident that the octagonal form of recuperator tile has definite advantages over square or round tile, both as to the structural arrangement of the tile within recuperator walls of different cross-sectional form and thermally by lowering the resistance to air flow and increasing the wiping action or contact of the air with the outer walls of the flue tile.

Although one embodiment of the invention has been herein illustrated and disclosed, it will be obvious to those skilled in the art that various modifications may be made in the details of construction without departing from the principles herein set forth.

We claim:

1. In a recuperator structure for furnaces, side, top and bottom walls constituting a closed chamber, a tile structure within said chamber consisting of refractory tile units joined at their ends by flange tile to constitute flues, and closure and baffle tile disposed between said flange tile to provide transverse flues, said flue tile units being of polygonal cross-section and mounted with their juxtaposed wall surfaces in parallelism.

2. In a recuperator structure for furnaces, side, top and bottom walls constituting a closed chamber, a tile structure within said chamber consisting of refractory tile units disposed in vertical rows joined at their ends by flange tile for engaging the flanges of adjacent rows of tile, and closure and baffle tile disposed between said flanged tile to provide transverse flues, said flue tile units being of polygonal cross-section and mounted with their juxtaposed wall surfaces in parallelism.

WILLIAM A. MORTON.
HOWARD F. SPENCER.
